UNITED STATES PATENT OFFICE.

ROBERT E. FIELD, OF ST. LOUIS, MISSOURI.

DESIGN FOR A BADGE.

Application filed September 1, 1923. Serial No. 7,141. Term of patent 14 years.

To all whom it may concern:

Be it known that I, ROBERT E. FIELD, a citizen of the United States of America, residing in the city of St. Louis and State of Missouri, have invented a new, original, and ornamental Design for Badges, of which the following is a specification, reference being had to the accompanying drawing, forming part thereof.

Fig. 1 of the drawing shows a face view of a badge made in accordance with my new design, and Fig. 2 is a side elevation thereof.

I claim:

The ornamental design for a badge, as shown.

ROBERT E. FIELD.
